UNITED STATES PATENT OFFICE.

ROBERT F. NADIG AND WILLIAM D. SOMERS, OF CLEVELAND, OHIO.

IRONING-BOARD CONSTRUCTION.

Application filed January 15, 1921. Serial No. 437,437.

To all whom it may concern:

Be it known that we, ROBERT F. NADIG and WILLIAM D. SOMERS, citizens of the United States, and residents of Cleveland, 5 county of Cuyahoga, State of Ohio, have jointly invented a new and useful Improvement in Ironing-Board Constructions, of which the following is a specification, the principle of the invention being herein explained and the best mode in which we have contemplated applying that principle, so as to distinguish it from other inventions.

This invention relates to an improved form of ironing board construction. More 15 particularly, it involves the type of ironing board which is adapted to be clamped in supporting engagement with some stationary object in the kitchen or laundry, such as a table or laundry tub, and is readily attachable thereto or removable therefrom.

In many types of ironing board construction, the supporting framework is of very light and flimsy character, and under the cross-strains involved in the ironing operations, soon loses its rigidity and becomes unsuitable for the work in hand. When such ironing boards are provided with attachments whereby they may be fastened to a table or wall, they are, ordinarily, of such 25 construction that they must be used in one particular place and are not readily adaptable for attachment to any convenient object, wherever desired.

The principal object of our invention is 30 to provide an ironing board construction of the type which is supported against a rigid object in the kitchen or laundry, and which will be readily adjustable so as to be attached to any such object in a minimum 35 amount of time and in such position that the ironing board proper will be horizontally disposed and the supporting portion thereof solidly and firmly clamped thereunder. Further objects of our invention will be disclosed in the course of the following description, among them the provision of means for 40 attaching the ironing board to either a horizontal support or one of vertical or angular position, as well as the supplying of a fastening device whereby the supporting structure devised by us may be attached to any ironing board of the usual construction and to either side of such board, as desired. To 45 the accomplishment of the foregoing and related ends, said invention, then, consists of

the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a side elevation showing our 65 ironing board construction attached to the edge of a table;

Fig. 2 is a bottom plan view of the clamping member of our construction, the supporting legs and brace arms being omitted; 70

Fig. 3 is an end elevation taken from the right-hand side of the view shown in Fig. 1;

Fig. 4 is an enlarged sectional view of the hinge construction employed by us taken along the line 4—4 in Fig. 1, looking in the 75 direction of the arrows;

Fig. 5 is an enlarged detail view, partly in section, showing a side view of the hinge construction when the ironing board is attached to a horizontal supporting element; 80

Fig. 6 is an enlarged plan view of the central portion of the clamping element employed;

Fig. 7 is a sectional detail view taken along the line 7—7 of Fig. 6, looking in the 85 direction of the arrows, showing the clamp in locking engagement with the locking-pin;

Fig. 8 is an enlarged vertical sectional view taken along the line 8—8 shown in Fig. 6, looking in the direction of the arrows, disclosing the character of the clamp terminals employed;

Fig. 9 is an enlarged sectional view of one 90 of the clamping racks taken along the line 9—9 shown in Fig. 2; and

Fig. 10 is a detail view showing our improved ironing board attached to the substantially vertical edge of a laundry tub.

In the form of our invention illustrated 100 in Figs. 1, 2 and 3, the ironing board 1 has secured to its under side a pair of depending ears 2 and a pair of longitudinal rack members 3. Hingedly connected to said ears, by means of pivot pins 4, are a pair of clamping sleeves 5 of rectangular cross-section and terminating in a pair of upstanding ears 6, each provided with suitable apertures for engagement over said pivot pins. Within 105 said respective sleeves, the upper ends of a pair of supporting legs 9 are engaged, the 110

outer faces thereof being beveled so that when the legs stand at approximately an angle of forty-five degrees to the ironing board, the beveled faces 11, 12 will be in horizontal and vertical positions, respectively. Approximately midway of the length of the pair of legs, a pivot-rod 15 is provided upon which there is mounted a brace member 16 formed of a pair of parallel arms connected by several transverse bracing members 17, 18. The upper end of each of said arms is tapered to a size to fit within the recesses provided in the rack members 3 secured to the ironing board and heretofore referred to. A pair of coil springs 21 are mounted upon the pivot-pin for the brace members, each being so fastened to its adjacent arm as to hold the same in engaging position with said rack. The lower ends of the pair of supporting legs are connected by means of a transverse member 22 and the under faces 23 of said lower ends are suitably rounded so as to have a substantial line of contact with the floor when our apparatus is placed in clamping position, whether such position is an elevated one or of less height than that ordinarily employed.

In order to utilize our invention upon any standard type of ironing board and to attach it to either side thereof and in this manner prevent the undue warping of the board through the use of one side exclusively, we have designed an adjustable clamping means which may be rigidly secured to such board with a minimum amount of trouble and with substantially the same degree of rigidity as where a permanently attached construction is employed. This clamping member, as is best shown in Fig. 2, comprises a base plate 31 provided at its forward edge with a pair of upturned gripping hooks 32 and centrally with a pair of pivot-pins 33 upon which are engaged, respectively, two lever arms 34 having at their outer ends upwardly turned hook elements 35 for engaging the ironing board. Adjacent the outer sides of the base plate are a pair of ears 36 providing points of attachment for pivot-pins 37 about which turn supplementary clamping members 51 designed for use when our apparatus is to be attached to a substantially vertical support, such as the edge of a laundry tub. Adjacent the outer ends of the clamping levers 34 are connected a pair of links 38, which, at their other ends, are pivoted upon a pin 39 which also serves as a pivot for a double link member 41, within which is pivoted the locking lever of the clamping member, comprising a double metallic strap member 42 pivoted centrally upon a pin 43 at the end of the double link 41 and carrying at its shorter end a locking-pin 44 adapted to be engaged in any one of a series of notches 45 provided upon one end of an extension link 46 which, at its other end, is connected by means of a

pair of short toggle links 47 with a pair of clamping arms 48 of substantially the same shape and inclination as the clamping arms 34 first referred to. The last-mentioned pair of clamping arms is connected midway by means of a transverse strap 49. Securely affixed to said strap are the pair of rack members 3, which are so positioned that they will be engaged by the upper ends of the brace arms, as heretofore described.

As is best illustrated in Fig. 10, the means for connecting our apparatus to a substantially vertical member 50, such as a laundry tub, comprises a pair of arms 52, each pivoted at one end to the pins 37 secured to the ears 36 of the base plate 31, and downwardly turned at their free ends. Adjacent each of said downwardly turned portions, a resilient gripping member 53 is secured, it being spaced a sufficient distance to be engageable over a laundry tub of the conventional form and usual thickness. The inner ends of these attaching devices, being pivoted upon the base of the plates, may be swung back to a position, shown in Figs. 1 and 2, under the central portion of the board when it is to be attached to a horizontal support. When the board is to be attached to a vertical member, these clamping elements last described are swung forwardly upon either side of the ironing board to a position indicated in dotted lines in Fig. 2 and in full lines in Fig. 10. In this position, as is clearly shown in Fig. 10, the vertical face 12 upon the upper end of the clamping legs will bear against its adjacent resilient element 53 and force the same into firm clamping contact with the object to which the board is to be attached, being locked into position by the engagement of the brace arms with the rack members. The clamping legs can be adjusted longitudinally to give any desired pressure to said clamping members. In other respects, the parts are identical with those employed where the board is to be attached to a horizontal member.

The operation of our construction, it is believed, will be obvious from the description above set forth. When the board is to be applied to a horizontal object, such, for example, as a table edge or the edge of the draining board upon a kitchen sink, the upper ends of the legs are permitted to project through the clamping sleeves to the position in which they will securely engage such object, with the ironing board in substantially horizontal position, and are then firmly clamped in said sleeves by means of the bolts and wing-nuts. The lower ends of the supporting legs will then be placed upon the floor and held thereon by the foot of the operator pressed against the lower cross-bar or the adjacent structure. The free end of the ironing board is then pulled upwardly and, because of the enormous

leverage in favor of the parts outwardly of the pivot, will, with but slight effort, produce a powerful gripping action upon the parts on the other side of said pivot.

5 Through the action of the springs upon the brace arms, the latter will be drawn against the locking racks on the underside of the board and will ride over the recesses therein until the desired degree of clamping adjustment of the board upon the table edge is secured. Through the minute adjustment of the projecting ends of the legs permitted by the sleeves, any desired amount of clamping pressure may be employed and the ironing board may be maintained in absolutely horizontal position regardless of the thickness of the edge of the supporting member to which it is applied. The same is true with regard to the gripping of a substantially vertical supporting member.

As has been above disclosed, we have provided in a single unitary construction an ironing board of universal application, in so far as the type of construction herein referred to is concerned. Thus, any standard size and style of ironing board may be converted in a few minutes into a brace-supported board of this character and a very rigid positioning of said board will result. The construction is simple in design and inexpensive to manufacture and carries as integral parts the necessary elements to operate in either of the positions heretofore described, without reassembling the parts thereof or laboriously substituting attachments in lieu of those originally used.

Other modes of applying the principle of our invention may be employed instead of the one explained, change being made as regards the mechanism herein disclosed, provided the means stated by any of the following claims or the equivalent of such stated means be employed.

We, therefore, particularly point out and distinctly claim as our invention:—

1. In apparatus of the class described, an ironing board, an adjustable supporting

member secured to the under-side thereof, 50 a pivoted leg clamping element mounted thereon, a supporting leg slidingly engaged in said leg clamping element, a rack member secured to said adjustable supporting member, and a brace arm pivoted to said 55 supporting member, its outer end engaging said rack member.

2. An ironing board attachment, comprising a supporting frame adapted to be rigidly clamped to the under-side of an 60 ironing board, pivoted leg clamping members and rack members provided on said frame, supporting legs associated with said leg clamping members, and brace members pivoted at one end to said legs, the other 65 ends thereof engaging said rack members.

3. An ironing board attachment, comprising a supporting frame adapted to be rigidly clamped to the underside of an ironing board, a pivoted leg clamping member 70 and rack member provided on said frame, a supporting leg adjustably associated with said leg clamping member, a brace member pivoted at one end to said supporting leg, the other end thereof engaging said rack 75 member, and clamping means mounted on said frame and adapted to be moved to project therebeyond so as to be operatively engaged by the upper end of said supporting leg. 80

4. An ironing board attachment, comprising a supporting frame adapted to be rigidly clamped to the under-side of an ironing board, pivoted leg clamping members and rack members provided on said frame, 85 supporting legs adjustably associated with said leg clamping members, brace members pivoted at one end to said supporting legs, the other ends thereof engaging said rack members, and pairs of resilient clamping 90 members pivotally mounted on said frame and adapted to be moved to project therebeyond so as to be engaged by the upper, ends of said supporting legs.

Signed by us this 10th day of January, 95
1921.

ROBERT F. NADIG.
WILLIAM D. SOMERS.
